**ADJUSTABLE TYPIST STAND FOR
HOLDING REFERENCE DATA**

Margerete Andrew, Rte. 4, Box 618,
Eugene, Oreg. 97405

Filed Aug. 3, 1972, Ser. No. 277,618

Term of patent 14 years

Int. Cl. D19—02

U.S. CL. D74—1 C

FIG. 1 is a frontal perspective view of the adjustable typist stand for holding reference data embodying my new design,

FIG. 2 is a rear perspective view of the stand shown in FIG. 1,

FIG. 3 is a side elevational view of the stand, and

FIG. 4 is a top plan view of the stand.

I claim:

The ornamental design for an adjustable typist stand for holding reference data, substantially as shown.
